By her Attorneys,

George M. Clapper, Inventor

Chas. Snow & Co.

UNITED STATES PATENT OFFICE.

GUSSIE M. CLAPPER, OF AXLINE, OHIO.

SHEARS.

SPECIFICATION forming part of Letters Patent No. 629,339, dated July 25, 1899.

Application filed April 1, 1899. Serial No. 711,332. (No model.)

To all whom it may concern:

Be it known that I, GUSSIE M. CLAPPER, a citizen of the United States, residing at Axline, in the county of Muskingum and State of Ohio, have invented a new and useful Shears, of which the following is a specification.

This invention relates to shears, and more especially to that class thereof employed for cutting or clipping the wool of sheep and other animals; and the object of the invention is to provide a simple, light, and inexpensive article of the character specified wherein the pressure of the blades one upon the other can be regulated with precision, thereby insuring clean even work without possibility of pulling the hair.

With these ends in view the invention consists in the novel combination of elements and in the construction and arrangement of parts, which will be hereinafter fully described and claimed.

To enable others to understand the invention, I have illustrated the preferred embodiment thereof in the accompanying drawings, forming a part of this specification, and in which—

Figure 1 is a top plan view of shears constructed in accordance with my invention. Fig. 2 is a side elevation of the same. Fig. 3 is a detail in perspective of the clamping-spring. Fig. 4 is a transverse section taken through the center of the spring.

Like characters denote like and corresponding parts in each of the several figures of the drawings.

The shears represented includes in its construction the juxtaposed cutter-plates C and C', which may be made of any suitable material and which are provided at their front ends with projecting bars or teeth 2 of tapered form and which are beveled along their opposite angular edges to produce cutting portions, and the cutting portions of the upper series of bars or teeth project in opposite directions to those on the lower set. The lower plate of the device is held stationary, while the upper plate is reciprocated across the same, so that the sharpened edges of the respective projecting bars 2 can coöperate to cut or clip the wool or hair of an animal, and

this operation can be rapidly and cleanly accomplished.

The handle of the shears is denoted by H, being formed from a single length of flat spring metal bent intermediate of its ends into substantially U shape, the opposite branches or members 3 and 4, respectively, having their extremities 10 twisted transversely at right angles to the plane of the respective members 3 and 4, so as to fit flat against the outer faces of the respective cutter-plates C and C', to which said connecting ends are fastened by rivets 11 or other suitable fastening means. By twisting the ends 65 of the handle the flat sides thereof are disposed in a convenient position for operating the device. One of the members, as 3, is preferably bowed outward slightly, as shown in Fig. 1, and is adapted to be held in the palm of the hand, the bowed portion fitting evenly within the palm. The opposite member 4 has a convolute form to accommodate the fingers of the hand, whereby the two members are given a shape to conveniently fit the 75 hand of the operator.

Ordinarily the branch 3 of the spring-handle H will be held in the hollow of the hand and the fingers will press the coöperating branch 4 inward, thereby moving the upper 80 bars or teeth 2 across their companions, and consequently compressing said branch 4, so that when it is released it can retract by its own action, and thereby return the several upper fingers to their initial positions, at 85 which point the operation will be repeated.

The pressure between the plates C and C' is regulated by the flat bowed spring 5, having openings 6 near its opposite ends to receive the bolts 7, carried by the under plate 90 C. These bolts extend through longitudinal slots 8 in the upper plate and are provided above the upper surface of the spring 5 with nuts 9, adapted to bind against the spring 5 and adjust its tension upon the upper plate, 95 and consequently to vary the contact of the latter with its companion. The opposite ends of the spring 5 bear firmly against the upper plate at points beyond the clamping-bolts 7 and serve to hold said upper plate with the 100 proper degree of pressure, which can be varied at will by changing the tension of the

spring 5. As the clipper is in use the cutting edges of the bars or teeth 2 are self-sharpening, and the contacting faces of the parts are worn away somewhat in operation; but this can be compensated for by tightening the spring, thereby insuring the proper contiguity between the two parts.

The shears constructed as aforesaid can operate with rapidity and can do close smooth work, and it will be evident that they are light and consist of a small number of parts, which can be produced and assembled for use at a low cost.

Changes in the form, proportion, size, and the minor details of construction within the scope of the appended claims may be resorted to without departing from the spirit or sacrificing any of the advantages of this invention.

Having thus described the invention, what I claim is—

1. A shears consisting of two juxtaposed cutting-plates carrying coöperating teeth, means for holding said plates in contact, and a handle consisting of a flat U-shaped spring having its ends bent transversely to its shoulder and secured to the outer faces of the juxtaposed plates, one branch of the spring being slightly bowed outwardly so as to fit within the palm of the operator's hand and the other branch having a convolute form to accommodate the operator's fingers.

2. The improved shears herein described and shown consisting of two juxtaposed plates carrying coöperating teeth, one of said plates being provided with transverse slots, a bowed spring extending over said slots and having its ends bearing on said plate beyond the slots, bolts carried by the non-slotted plate and projecting through said slots and the spring, thumb-nuts mounted on the said bolts and bearing against said spring, and a handle consisting of a flat U-shaped spring having its ends twisted in a plane at right angles to its shoulder and secured to the outer faces of the juxtaposed plates.

In testimony that I claim the foregoing as my own I have hereto affixed my signature in the presence of two witnesses.

GUSSIE M. CLAPPER.
